TREATMENT OF HYDROCARBON FRACTIONS
Kenneth Tupman and Peter Thomas White, Sunbury-on-Thames, England, assignors to The British Petroleum Company Limited, London, England, a British joint-stock corporation
No Drawing. Filed Oct. 24, 1961, Ser. No. 147,182
Claims priority, application Great Britain Oct. 28, 1960
10 Claims. (Cl. 208—264)

This invention relates to the treatment of hydrocarbon fractions, particularly petroleum fractions, boiling above 150° C., and the principal object of the invention is to provide a process by means of which the cloud point, pour point or freezing point of such fractions may be lowered.

According to the present invention a hydrocarbon fraction boiling above 150° C. is contacted with a catalyst comprising a platinum group metal on a refractory oxide support in the presence of hydrogen and added halogen at a temperature of at least 600° F. and a pressure of at least 100 p.s.i.g., the temperature and space velocity used being correlated to give a product boiling above 150° C. having a pour point at least 5° F. lower than the pour point of the feedstock.

It has been found that the presence of added halogen gives a markedly greater reduction in pour point compared with a similar operation without the halogen. In the case of the treatment of a heavy gas oil feedstock having a pour point of 50° F. with a platinum-alumina-halogen catalyst for example, the presence of an added halogen compound gave a reduction in pour point of 75° F. compared with a reduction of 10° F. for a similar operation without the halogen compound. The reduction of pour point of 75° F. was achieved with a yield of product (boiling above 150° C.) of 80% wt.

The term "fraction" as used in this specification includes both fractions which are distillable at normal or reduced pressure, for example gas oils and waxy distillates, and also residues and portions thereof, for example deasphalted residues. Particularly suitable fractions for use as feedstocks are distillate fractions boiling within the range 150 to 450° C. and more particularly within the range 250 to 450° C.

It has been found that it is not necessary to desulphurise the feedstock prior to submitting it to the pour point reduction process, although such a preliminary desulphurisation may be given if desired. When operating with a sulphur-containing feedstock (for example one with more than 0.1% wt. of sulphur) the process will normally effect considerable desulphurisation simultaneously with the lowering of the cloud point, pour point or freezing point. It has also been found that the process can be operated in the presence of considerable quantities of hydrogen sulphide, so that, for example, the process can be operated on the total effluent of a previous hydrocatalytic desulphurisation process.

If desired, a part only of a particular distillate may be treated by the process according to the invention and the resulting product blended with the untreated portion of the distillate to give a final product of reduced pour point.

The added halogen may be added to the reaction zone in any convenient manner, for example by injecting it directly into the reaction zone, by adding it to the hydrogen-containing gas used, or, preferably, by adding it to the feedstock. Examples of suitable halogens are fluorine,

2

chlorine, and bromine, the former being preferred because corrosion difficulties are minimised. The halogen may be added as such, or as a halogen compound which is decomposable to halogen under the reaction conditions.

5 Preferred halogen compounds are those having halogen together with one or more of the elements carbon, hydrogen or oxygen, for example hydrogen halides and halogen derivatives of aliphatic hydrocarbons having from 1 to 4 carbon atoms. The halogen is preferably added in an amount from 0.001 to 1% wt. by weight of feedstock.

The platinum group metal content of the catalyst may be within the range 0.01 to 5% wt., preferably 0.1-1.0% wt. The preferred platinum group metals are platinum and palladium. The refractory oxide support may be one or more of the oxides of metals of group II, III and IV of the periodic table. Preferably it contains a major proportion of alumina and it may also contain a minor proportion of one or more of the other oxides of metals of groups II, III and IV of the periodic table. Preferably 15 the amount of the group II, III or IV metal oxides is from 5-25% wt. of the support. Examples of suitable supports include alumina, silica/alumina, titania/alumina, zirconia/alumina and beryllia/alumina. The support material may also contain a minor proportion of one or 20 more compounds (including oxides) of non-metallic elements in groups III, IV and V for example boron or phosphorus, which may if desired be combined or mixed with any of the metal oxides of groups II, III and IV. Preferably 25 the amount of the compounds of the non-metallic elements is from 5 to 25% wt. of the support.

The catalyst may be halogen free or it may contain less than 1% wt. of halogen as disclosed in the complete specification of cognate U.K. patent applications Nos. 28,788/60, 37,123/60 and 5,774/61, or it may contain 35 at least 1% wt. of halogen as disclosed in the complete specification of U.K. patent application No. 37,126/60, in addition to the halogen present in the reaction zone by the addition of halogen. The catalyst may be employed as a fixed bed, a moving bed, or in the fluidised state.

An essential requirement to obtain pour point reduction with any given catalyst and operating conditions employed is a correlation of temperature and space velocity. In general the higher the temperature, the higher the 45 space velocity that can be employed, the upper limit of temperature, at any given space velocity, being determined by the amount of cracking occurring. The feedstock used, the activity of the catalyst used and the reduction of pour point required should also be taken into account 50 when selecting the process conditions. When treating the heavier feedstocks, for example, the operating conditions may be more severe (i.e. conditions of higher temperature and/or lower space velocity) than when treating lighter feedstocks.

When using a more active catalyst or when using a greater quantity of added halogen, less severe conditions may be used, an equivalent reduction in pour point being obtainable at a lower temperature and/or higher space velocity.

60 Preferably the temperature is below that at which substantial cracking occurs, and, for the purposes of the present specification substantial cracking is understood to occur when more than 20% wt. of the feedstock is converted to material boiling below 150° C. Preferably not more than 15% wt. of the feedstock is so converted. In practice the temperature will not normally exceed 950° F. and is preferably at least 700° F. Simi-

larly in practice the space velocity will not normally be less than 0.1 v./v./hr. and more particularly not less than 0.5 v./v./hr. Preferably it does not exceed 8 v./v./hr., and more particularly it does not exceed 5 v./v./hr. The pressure may be from 100 to 1500 p.s.i.g. and the hydrogen:hydrocarbon mole ratio from 1:1 to 20:1.

The process may be operated with or without a net hydrogen consumption. A net hydrogen consumption is generally favoured by increase in pressure and for any given temperature and space velocity the pressure at which the hydrogen consumption and hydrogen production are in balance is known as the equilibrium pressure. It is generally preferred to operate at or above this pressure because this results in an increase in the on-stream time before catalyst regeneration or replacement is necessary. Another advantage of this type of operation is, for example, that when processing feedstocks such as gas oils for the production of diesel oils, reduction of the diesel index is minimised or avoided. The principal advantage of operating below the equilibrium pressure is that a reduction in the specific gravity of the distillate is minimised or avoided.

Operation of the process using a fixed bed of catalyst is carried out in the normal manner, which is to increase the temperature gradually as the run continues in order to maintain the quality of the product at the desired level.

The process of the present invention will normally lower all the three points specified, viz. cloud point, pour point and freezing point. Which point is taken as the criterion for any particular operation will depend on the feedstock used and the use to which the product is to be put. The freezing point is normally only of importance with the lower boiling feedstocks.

In copending U.K. application No. 8,238/61 a process for the treatment of hydrocarbon fractions boiling above 150° C. to reduce their cloud point, pour point, or freezing point is described, in which the fractions are first treated to reduce content of aromatic hydrocarbons, or nitrogen compounds or both.

Such a process may, if desired, be combined with the process of the present invention, as may the processes disclosed in the copending applications referred to earlier, viz. in the complete specification of cognate U.K. appli-

used and inspection data on the feed and product were as follows:

Operating Conditions

Catalyst	Co—Mo/alumina
Pressure	p.s.i.g. 1000
Temperature	°F. 730
Space velocity	v./v./hr. 2.0
Gas recycle rate	s.c.f./b. 1000

10

Results

	Feed	Product
Specific Gravity at 60° F./60° F.	0.876	0.850
ASTM Distillation, °C.:		
IBP	298	146
10% Vol. Recovered at	320	278.5
50% Vol. Recovered at	345	333
90% Vol. Recovered at	380	371
FBP	395	391

Diesel Index	57/53	62/63
Cloud Point, °F.	58	60
Pour Point, °F.	50	50

The hydrofined product was then processed over a platinum catalyst to reduce its pour point. The catalyst composition was:

	Percent wt.
Platinum	0.75
Fluorine	0.35
Chlorine	0.35
Alumina	Balance

Four runs were carried out. In the first run there was no addition of a halogen compound to the reaction zone; in the second carbon tetrachloride was added to the feedstock in an amount to give 0.1% wt. of chlorine by weight of feedstock; in the third the amount of carbon tetrachloride was sufficient to give 0.5% wt. chlorine, and in the fourth tertiary butyl chloride was added in an amount to give 0.5% wt. chlorine.

After the processing the product was stabilised to remove a small proportion of material boiling below 150° C. and gave a gas oil of the required flash point (150° F.).

The process conditions used and results obtained are given in Table 1 below.

cation Nos. 28,788/60, 37,123/60 and 5,774/61 and in the complete specification of U.K. application No. 37,126/60.

The invention is illustrated by the following examples.

EXAMPLE 1

A heavy gas oil was hydrocatalytically desulphurised over a catalyst of 2.4% wt. cobalt oxide and 14.3% wt. molybdenum oxide on alumina. The process conditions

70
The results show the very much greater reduction in pour point obtainable when operating in the presence of a halogen compound.

EXAMPLE 2

A comparison of the effects of fluorides, chlorides and bromides on the pour point reduction of desulphurised heavy gas oil was carried out using the same catalyst, feedstock and feedstock preparation as those used in Ex-

ample 1. Three runs were carried out, in the first tertiary butyl chloride was added to the feedstock in an amount to give 0.1 percent weight chlorine by weight of feedstock; in the second tertiary butyl bromide was added to the feedstock to give 0.1 percent of bromine; in the third tertiary butyl fluoride was added to the feedstock to give 0.1 percent weight fluorine.

The process conditions used and results obtained were as follows:

Pressure, p.s.i.g.	500	500	500	500
Space velocity, v./v./hr.	1.0	1.0	1.0	1.0
Hydrogen rate (once through), s.c.f./b.	5,000	5,000	5,000	5,000
Feedstock	Desulphurised Heavy Gas Oil	Desulphurised Heavy Gas Oil containing 0.1 percent wt. Cl (added as tertiary butyl chloride)	Desulphurised Heavy Gas Oil containing 0.1 percent wt. Br (added as tertiary butyl bromide)	Desulphurised Heavy Gas Oil containing 0.1 percent wt. F (added as tertiary butyl fluoride)
Operating Temperature, °F	775	800	825	775
Feed				
Product Data:				
Cloud Point, °F	60	54	50	44
Pour Point, °F	50	50	45	40

EXAMPLE 3

The same feedstock, feedstock preparation and catalyst as that of Example 1 were used to study the effect of changes in process variables on the pour point reduction of desulphurised heavy gas oil containing carbon tetrachloride in an amount to give 0.1 percent weight chlorine by weight of feedstock.

The process conditions used and results obtained were as follows:

Hours on Stream	10-12	34-36	84-86	100-102	116-118	140-142
Operating Conditions:						
Feedstock						
Catalyst						
Reactor Pressure p.s.i.g.	750	750	750	750	750	750
Reactor temperature, °F	775	775	825	825	675	725
Space velocity, v./v./hr.	1.0	2.5	1.0	2.5	1.0	2.5
Gas recycle rate, s.c.f./b.	10,000	10,000	10,000	10,000	10,000	10,000
Feed						
Product (150° C.):						
Yield, percent wt.	90.2	94.9	86.6	93.0	97.7	97.6
Cloud Point, °F	60	28	46	6	36	58
Pour Point, °F	50	20	40	-15	30	50

This example illustrates the necessity of correlating the temperature and space velocity to give a reduction in pour point. At 675° F. and 1 v./v./hr., and 725 and 2.5 v./v./hr., the temperature is too low, at the space velocity used, to give pour point reduction. However, if the temperature is raised to 775, pour point reduction is obtained at both space velocities, being greater at the lower space velocity. Raising the temperature to 825° F. further reduces the pour point.

We claim:

1. A process for the treatment of distillate petroleum fractions boiling within the range 150-450° C. to lower the pour point at least 5° F. without material reduction in the specific gravity and diesel index of said distillate fractions, comprising contacting the distillate fraction as feedstock in a treating zone and in the presence of hydrogen and of halogen added to the treating zone in an amount from about 0.001 to 1% by weight of feedstock with a catalyst comprising a platinum group metal on a refractory oxide support, the hydrogen to hydrocarbon mole ratio being from 1 to 1 to 20 to 1; maintaining a selected temperature and a selected space velocity in said zone, said selected temperature in said zone being maintained at least at 700° F. but not higher than about 950° F. and being a temperature at which, at said selected space velocity, not more than 20% wt. of the feedstock

is converted to material boiling below 150° C. and said selected space velocity being at least 0.01 v./v./hr. but not higher than 8.0 v./v./hr. at which, at said selected temperature, not more than 20% wt. of the feedstock is converted to material boiling below 150° C.; maintaining a selected pressure in said zone in the range 100-1500 p.s.i.g., said selected temperature and said selected space velocity being correlated to reduce the pour point of the feedstock such that the pour point of the material of the

treated distillate fraction boiling above 150° C. is at least 5° F. lower than the pour point of the feedstock, and recovering the treated distillate fraction.

2. A process as claimed in claim 1 wherein the platinum group metal is palladium.

3. A process as claimed in claim 1 wherein the fraction is sulphur-containing.

4. A process as claimed in claim 1 wherein the halogen is fluorine.

5. A process as claimed in claim 1 wherein the halogen is added in the form of a compound of halogen in which halogen is combined with at least one of the elements carbon, hydrogen and oxygen.

6. A process as claimed in claim 1 wherein the catalyst contains from 0.01 to 5.0% wt. of the platinum group metal.

7. A process as claimed in claim 1 wherein the platinum group metal is platinum.

8. A process as claimed in claim 1 wherein the space velocity is at least 0.5 v./v./hr.

9. A process as claimed in claim 1 wherein the space velocity does not exceed 5 v./v./hr.

10. A process as claimed in claim 1 wherein the pressure is from 100 to 1500 p.s.i.g., and the hydrogen:hydrocarbon mole ratio is from 1:1 to 20:1.
